CLAIM

The ornamental design for a sewing machine carrying case, substantially as shown and described.

DESCRIPTION

FIG. 1 is a front perspective view of a sewing machine carrying case showing our new design;

FIG. 2 is a perspective view thereof with the front flap opened;

FIG. 3 is a top plan view;

FIG. 4 is a front elevational view;

FIG. 5 is a right side elevational view;

FIG. 6 is a rear elevational view;

FIG. 7 is a left side elevational view;

FIG. 8 is a bottom plan view; and

FIG. 9 is a top plan view of the sewing machine carrying case in fully opened condition.
